MUSIC SHEET TURNER

Filed April 26, 1924

UNITED STATES PATENT OFFICE.

JESSE TAYLOR GENTRY, OF LOS ANGELES, CALIFORNIA.

MUSIC-SHEET TURNER.

Application filed April 26, 1924. Serial No. 709,155.

This invention relates to an appliance for turning the pages of music either in a book or sheet form; and an object is to provide a simple means for turning the sheets quickly and efficiently at the proper time in a performance without laborious or troublesome effort of a performer; and without interrupting the continuity of the music.

It is customary in a recital comprising several pages, for a performer to have an attendant to turn the sheets at the proper time, which arrangement detracts from the performance and is rarely satisfactory, as it is seldom that two persons can mentally read music in substantially the same time.

Many performers read their music in close relationship to its production while others read it far in advance; and this great difference in music reading by the performers makes the art of page turning by an attendant uncertain of satisfactory results; also the extending of an attendant's hand across a page to turn a sheet oftentimes results detrimental to good production; and an object of the invention is to provide a simple and effective means for turning the sheets at substantially the right times so that a performer can render a production from page to page without confusing interruptions.

Another object of the invention is to provide a music sheet turner that is especially adapted for use of a performer employing both hands in rendering a composition. To that end, I provide a music stand having a sheet turner connected therewith that can be operated by a foot pedal to automatically turn the sheets one by one, and at the proper time.

Another object is to provide a music sheet turner that will hold the pages straight and smooth; so that they will not fold or be displaced when turned by the appliance.

Another object of the invention is to provide a music sheet turner that will turn the sheets without causing an excessive amount of noise. To that end, I provide a means for actuating the sheet turning arms comprising coiled springs the tensions of which are released after the arms have consummated the first half of their sheet turning movement, so that in the last half they are carried on to a full page turning movement by momentum. This momentum is gradually overcome by air resistance against the turning sheet so that when the full turn of

the sheet is consummated the turned sheet stops noiselessly.

Another object is to provide means for turning the music sheets separately and in consecutive order so that confusion cannot arise by having two or more of the sheets turned at the same time. Such confusion often arises in a performance by an attendant inadvertently turning two or more sheets that cling or stick together; and an object of the invention as stated is to provide means for preventing more than one sheet to be turned at a single time.

Features of the invention are shown in the construction, combination and arrangement of the various parts whereby a music sheet turned embodying neatness, durability, and great usefulness is produced.

Other objects, advantages and features of invention may appear from the accompanying drawings, the subjoined detailed description and the appended claims.

The accompanying drawings illustrate the invention.

Figure 1 is a front view of a music sheet turner constructed in accordance with this invention, and showing an open sheet of music thereon in position for the succeeding pages to be turned by the appliance.

Fig. 2 is a side view of the appliance as seen from the right side of Fig. 1, showing a part of the pedestal broken away to disclose a portion of the cable connecting the arm releasing appliance with the foot pedal.

Fig. 3 is an enlarged fragmental side view analogous to the upper portion of Fig. 2; showing the sheet turning arms set in position to turn the music sheets.

Fig. 4 is an enlarged fragmental front view analogous to the upper portion of Fig. 1 with the music removed.

Fig. 5 is an enlarged fragmental section on line α^5 , Fig. 4, showing a detail of the finger on which is mounted the clamp for holding an outside edge of the sheets of music.

Fig. 6 is an enlarged fragmental section on line α^6 , Fig. 4, showing a detail of the clamp for holding the top edge of the music backing or cover to the music rack.

Fig. 7 is an enlarged sectional view on line α^7 , Fig. 4, showing a clamp attached to an arm and adapted to hold the bottom edges of the sheets of music that are to be turned.

Fig. 8 is an enlarged fragmental cross

section on line x^8 , Fig. 4, showing a hinged connection of the rack wings to the rack posts, and a back stop in connection therewith.

5 Fig. 9 is an enlarged fragmental section on line x^9 , Fig. 4, showing a detail of a clamp for holding the outside edges of the sheets of music that are to be turned.

10 Fig. 10 is a perspective view of one of the coiled springs for actuating the sheet turner arms.

Fig. 11 is an enlarged fragmental section on lines x^{11} , Figs. 1, 2, 3, 4.

15 Fig. 12 is a fragmental section on line x^{12} , Fig. 11, showing all of the music turning arms extended in their normal position to the left of the rack.

20 Fig. 13 is a fragmental section analogous to Fig. 12, showing all of the music turning arms extended to the right of the rack in position to be actuated by their respective springs to turn the sheets of music when the arms are released by the foot pedal.

25 Fig. 14 is a fragmental cross section on line x^{14} , Fig. 13, showing the means for holding and releasing the music turning arms.

30 Fig. 15 is a sectional view analogous to Fig. 14, showing the means actuated to release one and hold the other arms.

Fig. 16 is a fragmental cross section on line x^{16} , Fig. 12, showing the means for supporting and actuating the page turning arms and springs.

35 Fig. 17 is a fragmental section on line x^{17} , Fig. 13, showing the turning arms in a set position to turn the music pages when released; and showing one of the arm actuating springs under tension.

40 Fig. 18 is a fragmental side view of the bearing end of one of the sheet turning arms detached from the appliance.

Fig. 19 is a plan view of the arm shown in Fig. 18.

45 Fig. 20 is a fragmental perspective view of one of the sheet turning arms.

The appliance comprises a hollow pedestal 1 that supports a housing 2 in which the means for actuating the sheet turning arms 3 is mounted and arranged.

50 At the rear of the housing 1 is a riser 4 on which the music rack 5 is supported.

The rack 5 can be constructed and arranged as desired; as shown it comprises a pair of wings 6 secured by hinges 7 to the posts 8 that extend upward from and which are secured to the riser 4; also the posts 8 are supported by offset extensions 9 that are secured to the housing 2, see Figs. 2, 3.

60 At the bottom of the wings 6 is arranged a grooved rest 10 that is adapted to receive the bottom edges of the first and last sheet of a piece of music, or the cover when the music is in book form; and also clamps 11 are provided for holding the top edges of the

first and last sheets or book cover to the rack; it being understood of course when the music is in book form that all of the sheets except the intermediate sheets to be played are seated on the rest 10 and secured at the top by the clamps 11; and a back stop 12 is secured adjacent the top of the posts 8 against which the wings 6 rest when they are in open position, see Fig. 8.

The housing 2 is provided with a tapered hollow base 13 that is secured to the top end of the pedestal 1 and this base is arranged so that it holds the housing 2 and rack 5 in a position inclined backward from the front of the pedestal as shown in the drawings.

The housing 2 comprises a platform 14 to which is secured the end plates 15 and back plate 16 integral at its upper end with the riser 4. The ends 15 are provided with angle irons 17 that form guides for the detachable front plate 18; and also the ends 15 carry the bars 19 that form supports for the split removable cover 20 of the housing 2.

The cover 20 is provided with an opening 21 in the center of which is arranged a bearing pin 22 on which the page turning arms 3 are pivotally mounted.

Pin 22 is supported by a bracket 23 that is secured to the platform 14 and back plate 16.

There are preferably four of the page turning arms 3, but there can be more or less if desired; and these arms are provided with bearing ends having upper and lower bearings 24, 25 that are spaced apart and arranged so as to be pivotally mounted on the pin 22 between the coiled springs 26 and 27; and these springs are adapted to yield slightly when any of the arms are moving so that the yielding of the springs will compensate for a change in position of the bearings.

The bearings 24, 25 of the arms 3 are spaced apart by bars 28, each of which is provided with a lug 29 to which one end 30 of a coiled spring 31 is adapted to be attached. There are four of the coiled springs 31, or one for each arm; and they are also mounted on pin 22 and arranged between the bearings 24, 25 of the arms.

In constructing the bearings 24, 25 they are first stamped out and flattened with the bars 28; after which the arms are arranged side by side and the bearings arranged in a turner that is actuated to give the assembled bearings a half turn so that as finished they are closely fitted together and arranged at right angles to the bars 28 and arms 3.

The other end portions 32 of the coiled springs 31 are arranged at an angle to the ends 30 and are adapted to engage a post 33 when the arms 3 are moved one half of the arc from their normal or rest position shown in Figs. 11, 12 to an operative posi-

tion shown in Figs. 13, 14, 15 and 17, in which latter position the springs 31 are under sufficient tension to force the arms 3 one-half the distance from operative toward 5 normal position when they are released.

The arms 3 are preferably formed of sheet metal, and arranged to move in an arc of one hundred and eighty degrees; and in this movement from an operative to a normal 10 position they are impelled one half of the distance or ninety degrees by tension of their respective springs; and the remainder of the distance they move by momentum from the springs; and during the movement by 15 momentum the arms are retarded by air resistance on the music sheet so that by the time they approach a fully idle position their progress is relatively slow, and they stop without causing a noise. 20 The arms 3 are held against the tension of the springs 31 by means of a dog 34 that is integral with and carried by a reciprocating frame 35. This frame has bearings 36 slidably mounted in guides 37 of a bracket 38; 25 and the frame is supported by springs 39 engaging the guides. Also the frame 35 has a bearing 40 that is slidably mounted in a guide 41 secured to the bracket 38, by which arrangement of parts the frame is held upright and can reciprocate in its bearings. 30

Normally the frame 35 is supported in position whereby the dog 34 engages with extensions 42 to hold the arms 3 against the tension of the springs 31. The frame 35 is 35 moved down against the supporting springs 39 to release the dog 34 from the extensions 42; and it is so actuated by means of a draw rod 43 that connects the frame 35 with an intermediate lever 44 pivoted at 45 and which has its free end 46 connected by a cable 47 to a tread lever 48 that is pivoted at the bottom of the pedestal 1 by a bearing 49.

The tread lever 48 is arranged so that it can be easily reached and operated by either 45 a standing or sitting performer.

When the tread lever 48 is actuated it forces the frame 35 downwardly and the dog 34 is moved below the lower edges of the extension 42 so that an arm is released and can be turned back from set to normal position by the springs 31.

To prevent more than one arm from being released at one time a wedge 49 is pivotally mounted on a pin 50 in the frame 35 in position to descend in time with the movement of the dog 34 and wedge in between the extension 42 of the arm released and the adjacent extension to hold back the other arms. 55

In other words the wedge moves down at the same speed as the dog and wedges in between the two extensions adjacent the dog before the one contacting with the dog is released; so that by reciprocating the frame 35 downward repeatedly by the foot lever 48 the arms 3 can be consecutively released 60

to move from a set to normal position and thereby turn the music sheets attached thereto.

A spring 51 and set screw 52 are provided for normally holding the wedge 49 in a position to engage or fit in between the extensions 42 when the frame 35 is moved downward; and the spring also permits the wedge to be moved into the position shown by dotted line in Fig. 14 to form a clearance 75 between the points of the dog and wedge through which the extensions 42 can be passed when the arms 3 are to be set.

The top edges of the extensions 42 are beveled as shown in the drawings so that 80 the point of the wedge 49 can easily pass between them to coact with the dog 34 to release one of the arms and hold back the others.

Each of the arms 3 are provided with 85 sliding fingers 53 that are constructed as best shown in Figs. 4, 5. As seen therein the fingers 53 have base ends 54 provided with rectangular openings through which the arms 3 extend, and on which the fingers are 90 slidable so that they can be moved toward or away from the pivoted ends of the arms.

The fingers 53 are provided with sheet clamps 55 that are slidably mounted on the fingers 53 as illustrated in Fig. 9. 95

These clamps comprise the fixed jaw 56 provided with lugs 57 between which a movable jaw 59 is mounted on a pin 58; and a spring 60 normally holds the jaws in engagement and between the jaws are fitted 100 the music sheets 61 that are to be turned.

The arms 3 are also provided with clamps 62 that are adapted to be fitted over the bottom edges of the sheets 61 to be turned. 105

The clamps 62 comprise the spring members 63, 64 that are riveted together adjacent their lower ends; and the lower ends are bent to form sockets 65 that are adapted to be fitted over and ride on the saddles 66 that are integral with the arms 3 as best shown 110 in Fig. 20, there being one of these clamps 62 for each of the arms.

As previously stated the back or cover of the music has the bottom edges seated in the rest 10 and the upper edges are held by the clamps 11 which, as shown in Figs. 4, 6, are adapted to slide up and down on the beveled slats 77 of the holder 5. The clamps 11 have movable jaws 78 pivoted at 115 79 that are adapted to be pressed into engagement with the backs or covers 80 of the sheet music by springs 81, see Fig. 6.

In operation the music cover is placed on and secured to the rack 5 as described; then the sheets to be turned are secured to the arms 3 by the clamps 55, 62, after which the arms 3 are moved from their normal to their set position against the tension of the coiled springs 31. In which position the first arm to be actuated has its extension 42 120 125 130

engaging the dog 34 and the other extensions arranged in order to consecutively engage the dog after the first and succeeding arms have been actuated.

5. When the first sheet of music is to be turned the foot pedal 48 is actuated to move the frame 35 downward, which also will move the dog 34 to release the first arm, and simultaneously move the wedge 49 to engage and hold back the other arms.

10 The tension on spring 31 will force the released arm from a set toward normal position; and as previously stated the spring tension is released after half of the sheet turning movement is consummated; and momentum completes the movement.

15 After the first sheet has been turned the foot pedal is released so that springs 39 force the frame 35 upward to disengage the wedge 49 and engage the dog 34 with the extension 42 of the next arm to be actuated.

20 Repeated actuation of the foot pedal 48 will release the arms 3 consecutively and at the right time for turning the sheets of music.

25 I claim:

30 1. The music sheet turner set forth comprising a hollow pedestal; a housing supported by said pedestal; a music rack on said housing; arms pivotally mounted within said housing and adapted to move in an arc of a circle and sheet clamps on the arms detachably connected to the music sheets, said arms normally extending to the left hand side of said rack; coiled springs for actuating said arms that are out of tension when said arms are extended toward the left hand side of said rack; means for placing said springs under tension during the last half of 35 the movement of said arms as they are moved in an arc from the left to the right hand side of the rack; a dog for holding said arms when extended toward the right hand side of said rack; a wedge for holding the arms extended toward the right of said rack and means for simultaneously releasing said wedge and actuating said dog to operate said arms separately and in consecutive order.

40 2. The music sheet turner set forth comprising a hollow pedestal; a housing supported by said pedestal; a music rack on said housing; arms pivotally mounted within said housing and adapted to move in an arc of a circle and sheet clamps on the arms detachably connected to the music sheets, said arms normally extending to the left hand side of said rack; coiled springs for actuating said arms that are out of tension when said arms are extended toward the left hand side of said rack; said springs adapted to be placed under tension during the last half of the movement of said arms as they are moved in an arc from the left to the right hand side of the rack; a dog for holding and 45 releasing said arms when extended toward

the right hand side of said rack; a wedge co-acting with said dog to hold back the arms extended toward the right of the rack when said dog released an arm; and a foot pedal for actuating said dog and wedge.

50 3. The music sheet turner set forth comprising a hollow pedestal; a housing supported by said pedestal; a music rack on said housing; arms pivotally mounted within said housing and arranged adjacent the base of and normally extending toward the left hand side of said rack; clamps carried by said arms that are adapted to be attached to and hold sheets of music that are to be turned; coiled springs adapted to be placed under tension during the last half of the movement of said arms as they are moved in an arc from the left to the right hand side of said rack; a dog for holding said arms and releasing them separately and consecutively when they are extended to the right hand side of said rack and against the tension of said springs; a pivoted wedge co-acting with said dog to hold back the arms extended toward the right of the rack 55 against the tension of said spring when said dog is actuated to release an arm; an intermediate lever for actuating said dog and wedge; and a cable connecting said intermediate lever with a foot pedal said cable 60 extending through said hollow pedestal.

65 4. The music sheet turner set forth comprising a hollow pedestal; a housing supported by said pedestal; a music rack on said housing; arms pivotally mounted within said housing and adapted to move in an arc of a circle and figures adjustably mounted on said arms, sheet clamps slidable on said fingers and being detachably connected to the music sheets, said arms normally extending to the left hand side of said rack; coiled springs for actuating said arms that are out of tension when said arms are extended toward the left hand side of said rack; said springs being under tension during the last half of the movement of said arms as they are moved in an arc from the left to the right hand side of said rack; an arm extending from said spring, a post, said arm being adapted to engage said post, and place said spring under tension, only during the last half of the movement of said first named arms as said first named arms are moved from left to right; and means for holding said arms when extended toward the right hand side of said rack, and for releasing said arms separately and in consecutive order.

70 5. The music sheet turner set forth comprising a hollow pedestal; a housing supported by said pedestal; a music rack on said housing; arms pivotally mounted within said housing and adapted to move in an arc of a circle; clamps on said arms adapted to be detachably connected to the music

sheets, said arms normally extending toward the left hand side of the rack; coiled springs for actuating the arms that are out of tension when said arms are extended toward the left hand side of said rack, said springs adapted to be placed under tension during the last half of the movement of said arms, as the latter are moved in an arc from the left to the right hand side of the rack; a dog for holding and releasing said arms separately and in consecutive order when ex- tended toward the right hand side of said rack; a pivotally mounted wedge coacting with said dog to hold back the arms extended toward the right of the rack, when said dog releases an arm and a foot pedal for actuating said dog and wedge.

In testimony whereof, I have hereunto set my hand at Los Angeles, California, this 17th day of April, 1924.

JESSE TAYLOR GENTRY.
